E. BOMMER,

DOUBLE ACTING SPRING HINGE.
APPLICATION FILED DEG. 1, 1908.

941,185.

Patented Nov. 23, 1909.

UNITED STATES PATENT OFFICE.

EMIL BOMMER, OF NEW YORK, N. Y.

DOUBLE-ACTING SPRING-HINGE.

941,185.

Specification of Letters Patent. Patented Nov. 23, 1909.

Application filed December 1, 1908. Serial No. 465,571.

To all whom it may concern:

Be it known that I, EMIL BOMMER, a citizen of the United States of America, residing in New York, in the borough of Brooklyn, county of Kings, and State of New York, have invented certain new and useful Improvements in Double-Acting Spring-Hinges, of which the following is a specification.

10 This invention relates to certain improvements in the double-acting spring-hinge for which Letters Patent No. 898,031 were granted to me on September 8, 1908, the improvements being designed with a view of 15 simplifying and cheapening the construction of the hinge.

In practically testing the double-acting spring-hinge referred to, it was found that the use of the ball-bearings for the same 20 rendered it considerably expensive, for the reason that it was necessary to have two ball-bearings in each double-acting spring-hinge, and as there are four spring-hinges, namely, two for each door, four ball bearings are 25 necessary for each door and eight ball-bearings for a pair of doors. In many cases, however, the doors, especially those of lighter weight, can be used with almost the same facility with double-acting spring-hinges 30 without ball-bearings, by substituting therefore simply a loose cylindrical washer, by which the appearance of the double-acting spring-hinge is preserved, while the cost of the same is considerably reduced; and for 35 this purpose the invention consists of a double-acting spring-hinge which comprises two spring-barrels, a web connecting said barrels, a flange for each spring-barrel provided with perforated ears at its upper and 40 lower ends, pintle-sockets attached to said ears, two fixed spring-holders located at diagonally opposite ends of the respective spring-barrels, loose washers interposed between the diagonally arranged fixed spring-holders and the pintle sockets respectively 45 below and above the lower and upper ends of the barrels, adjustable tension-collars at the diagonally opposite ends of the respective spring-barrels interposed between the extreme 50 upper and lower ends of the spring-barrels and the pintle sockets, the adjustable tension-collars being provided with interior spring-holding lugs extending into the barrels for receiving the ends of the springs 55 that are interposed between the fixed spring-holders at one end and the adjustable ten-

sion-collars at the opposite end of the barrels, said springs being coiled respectively in opposite direction to each other.

The accompanying drawing represents a 60 side-elevation and a vertical section of a pair of double-acting spring-hinges containing my improvements.

The general construction of my improved double-acting spring-hinge is the same as 65 that shown and described in the prior patent referred to. The spring-hinge consists of two spring-barrels a , a^1 , which are connected by a plate or web b that extends between the two spring-barrels. The spring-barrels are provided with flanges c , c^1 , at the upper and lower ends of which are arranged perforated ears d , d^1 at right angles to the flanges and through the perforations of which the pintles i of the spring-barrels 75 are passed. At the upper end of one spring-barrel and at the lower end of the other spring-barrel are arranged adjustable tension-collars f , f^1 , which are provided at the inside of the spring-barrels with seats or 80 lugs for receiving one end of the spiral springs s , s^1 that are located in the spring-barrels. In the opposite ends of the spring-barrels are located fixed spring-holders g , g^1 , which are likewise provided with seats or 85 lugs for receiving the opposite ends of the springs s , s^1 , said spring-holders being rigidly attached to the ends of the spring-barrels preferably by suitable pins g^2 which pass through holes in the spring-barrels into 90 sockets g^3 in the spring-holders. For the stronger and larger sizes of double-acting spring-hinges pintle-sockets e , e^1 are employed. Adjacent to the fixed spring-holders g , g^1 and interposed between the same 95 and the adjacent pintle-sockets are loose washers h , h^1 of cylindrical shape, which are made of the same size as the exterior portions of the tension-collars, and which take up the weight of the load and reduce 100 the friction of the same with the upper end of one spring-barrel and with the pintle socket below the opposite spring-barrel. The pintles i pass centrally through the perforations of the ears of the flanges, pintle-sockets, tension-collars, springs, spring-holders, and loose washers and are provided 105 at their upper and lower ends with ball-shaped tips or terminals i^1 which are screwed onto the threaded ends of the pintles or otherwise attached thereto. One loose washer h is located adjacent to the fixed

spring-holder g at the extreme lower end of the spring-barrel a , while the loose washer h^1 is located adjacent to the fixed spring-holder g^1 at the extreme upper end of the other spring-barrel a^1 , both washers being located outside of the spring-barrels and respectively between the lower and upper edges of the spring-barrels a, a^1 and the adjacent pintle-sockets e, e^1 .

10 The loose washers h, h^1 , besides reducing the friction of the load, serve for the purpose of imparting, together with the adjustable tension-collars, to the four hinges when applied to a pair of doors the same appearance at opposite sides of the casing to which they are attached, and give, furthermore, a perfectly symmetrical appearance to both sets of spring-hinges whether viewed from the inside or outside of the room when 15 the doors are in inwardly-open or outwardly-open position, in the same manner as with the spring-hinges described in the prior patent referred to, in which separate ball-bearings are interposed between the 20 spring-barrels and pintle-sockets.

25 The springs s, s^1 , which are located in the barrels a, a^1 , are coiled respectively in opposite directions, that is to say, one barrel is provided with a spring coiled in the 30 right-hand direction and the other barrel with a spring coiled in the left-hand direction. In one barrel the adjustable tension-collar f is located at the upper end and the fixed spring-holder g and loose washer h 35 at the lower end, while in the other spring-barrel the fixed spring-holder g^1 and the

loose washer h^1 are located at the upper end and the adjustable tension-collar f^1 at the lower end of the barrel, as shown in the figure of the drawing.

40

Having thus described my invention, I claim as new and desire to secure by Letters Patent:

A double-acting spring-hinge comprising in its construction two spring-barrels, a web connecting the barrels, flanges on the spring-barrels having perforated ears, pintle-sockets applied to said ears, two fixed spring-holders located at the lower and upper portions of the respective spring-barrels, loose washers interposed between said spring-holders and the pintle-sockets adjacent thereto, two adjustable tension-collars provided with interior spring-holding lugs and located diagonally opposite to each other 55 and being interposed between the upper and lower ends of the respective spring-barrels and the pintle-sockets, pintles passing centrally through the spring-barrels, and springs interposed between the lugs of the 60 fixed spring-holders and the lugs of the adjustable tension-collars in said spring-barrels and coiled respectively in opposite direction to each other.

50

55

In testimony, that I claim the foregoing 65 as my invention, I have signed my name in presence of two subscribing witnesses.

EMIL BOMMER.
